Inventors.

UNITED STATES PATENT OFFICE.

ALFRED H. RAMEY, FRANK D. ROLLINS, AND LEWIS H. RICE, OF AURORA, ILLINOIS.

DESIGN FOR AN INHALER, &c.

SPECIFICATION forming part of Design No. 26,636, dated February 16, 1897.

Application filed December 24, 1896. Serial No. 616,926. Term of patent 14 years.

To all whom it may concern:

Be it known that we, ALFRED H. RAMEY, FRANK D. ROLLINS, and LEWIS H. RICE, of Aurora, in the county of Kane, and in the State of Illinois, have invented a new and original Design for an Inhaler and Injector; and we do hereby declare that the following is a full, clear, and exact description thereof, reference being had to the accompanying drawing, in which the figure is a perspective view of our appliance.

The object of our invention is to provide a device of novel shape for applying medicine to the passages of the nose and throat; and to this end said invention consists in the design for such a device, substantially as hereinafter shown.

The leading feature of our design is a body from which project two tubes at an angle to each other.

In the embodiment of our design as illustrated in the drawing the main body portion of the inhaler and injector is in the form of a cylinder A, that constitutes the receptacle for the medicine to be employed, one end of the same being supplied with a removable cap or cover B. Extending from the side of the cylinder A, close to one end, is a small

tube C, while on the opposite side of said cylinder is a second tube D, that from a point 30 near the end of the cylinder opposite that where the tube C is located extends alongside of the cylinder and projects beyond the end thereof at which the tube C is placed. The projecting portion of said tube D inclines 35 slightly inward toward the cylinder, and the tube C inclines so as to form an acute angle with the projecting portion of the tube D, such relative position of the tubes being given to enable the tube C to be inserted in one of 40 the nostrils and the tube D to be placed in the mouth.

Having thus described our invention, what we claim is—

The design for an inhaler and injector, substantially as herein set forth.

In testimony that we claim the foregoing we have hereunto set our hands this 18th day of December, 1896.

ALFRED H. RAMEY.
FRANK D. ROLLINS.
LEWIS H. RICE.
